US00D873816S

(12) **United States Design Patent** (10) **Patent No.:** **US D873,816 S**
Wu et al. (45) **Date of Patent:** **** Jan. 28, 2020**

(54) **NOTEBOOK COMPUTER**

- (71) Applicants: **Tung-Ying Wu**, Taipei (TW);
Ming-Chung Liu, Taipei (TW);
Kuan-Chang Lee, Taipei (TW)
- (72) Inventors: **Tung-Ying Wu**, Taipei (TW);
Ming-Chung Liu, Taipei (TW);
Kuan-Chang Lee, Taipei (TW)
- (73) Assignee: **COMPAL ELECTRONICS, INC.**,
Taipei (TW)
- (**) Term: **15 Years**

(21) Appl. No.: **29/630,420**

(22) Filed: **Dec. 20, 2017**

(51) **LOC (12) Cl.** **14-02**
(52) **U.S. Cl.**
USPC **D14/315**

(57) **CLAIM**

The ornamental design for a notebook computer, as shown and described.

DESCRIPTION

FIG. 1 is a perspective view of a notebook computer showing our new design;
FIG. 2 is another perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a cross-section view taken along the line 9-9 of FIG. 5 with the internal parts being omitted;
FIG. 10 is enlarged view thereof encircled portion of FIG. 1;
FIG. 11 is enlarged view thereof encircled portion of FIG. 2;
FIG. 12 is enlarged view thereof encircled portion of FIG. 3;
FIG. 13 is enlarged view thereof encircled portion of FIG. 3;
FIG. 14 is enlarged view thereof encircled portion of FIG. 7;
FIG. 15 is enlarged view thereof encircled portion of FIG. 8;
and,
FIG. 16 is a perspective view thereof showing the display is moved.
The dashed broken lines showing portions of the notebook computer form no part of the claimed design.
